UNITED STATES PATENT OFFICE.

FRED A. CONRAD, OF MILWAUKEE, WISCONSIN, ASSIGNOR TO AMERICAN LACE PAPER COMPANY, OF MILWAUKEE, WISCONSIN, A CORPORATION OF WISCONSIN.

DESIGN FOR A NAPKIN.

Application filed April 25, 1929. Serial No. 31,007. Term of patent 7 years.

To all whom it may concern:

Be it known that I, FRED A. CONRAD, a citizen of the United States, residing at Milwaukee, in the county of Milwaukee and State of Wisconsin, have invented a new, original, and ornamental Design for Napkins, of which the following is a specification, reference being had to the accompanying drawings, forming part thereof.

The drawing shows a fragmentary portion of the napkin including a complete quarter thereof, the remaining quarters being identical therewith.

The geometrical figures appearing on the face of the napkin constitute areas in a different plane than the body portion of the napkin.

I claim:

The ornamental design for a napkin substantially as shown and described.

FRED A. CONRAD.
